CLAIM

The ornamental design for toy figurine, as shown and described.

DESCRIPTION

FIG. 1 is a front perspective view of the toy figurine, showing our new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The equally spaced broken lines on the neck and torso of the toy figurine illustrate surface ornamentation and form part of the claimed design.

1 Claim, 5 Drawing Sheets
